DESIGN FOR A COMBINATION FUSE LOCK AND PULLER

David Conlan, New York, N. Y., assignor to
Conlan Electric Corporation, New York, N. Y.

Application December 6, 1944, Serial No. 116,750

Term of patent 14 years

(Cl. D26—1)

To all whom it may concern:

Be it known that I, David Conlan, a citizen of the United States, residing at New York, in the county and State of New York, have invented a new, original, and ornamental Design for a Combination Fuse Lock and Puller, of which the following is a specification, reference being had to the accompanying drawing forming part thereof.

Fig. 1 is a top perspective view of a combination fuse lock and puller embodying my new design; and

Fig. 2 is a bottom perspective view of the same.

I claim:

The ornamental design for a combination fuse lock and puller, substantially as shown.

DAVID CONLAN.
